UNITED STATES PATENT OFFICE.

CARL WILLIAM KETTLER, OF WARWOOD, WEST VIRGINIA.

COMBINED FOLDING IRONING-BOARD, CLOTHES-BASKET, AND CLOTHES-RACK.

1,188,181.

Specification of Letters Patent. Patented June 20, 1916.

Application filed February 5, 1916. Serial No. 76,382.

To all whom it may concern:

Be it known that I, CARL W. KETTLER, a citizen of the United States, and a resident of Warwood, in the county of Ohio and 5 State of West Virginia, have invented certain new and useful Improvements in Combined Folding Ironing-Boards, Clothes-Baskets, and Clothes-Racks, of which the following is a specification.

10 My invention is an improvement in a combined folding ironing board, clothes basket and clothes rack, and the invention has for its object to provide a device of the character specified, which may be collapsed into 15 folded position for storage or transportation, or expanded into a condition for use, and which may be converted at will into an ironing board and a support therefor, or into a clothes basket, and which in either 20 form has in connection therewith a rack for the clothing.

In the drawings: Figure 1 is a perspective view of the improved board; Fig. 2 is an enlarged section taken substantially on the line 25 2-2 of Fig. 1, looking in the direction of the arrow adjacent to the line; Fig. 3 is a transverse vertical section showing the board expanded and set up; Fig. 4 is a similar view showing the board folded or collapsed; Fig. 30 5 is a partial top plan view of the board support, and Fig. 6 is an enlarged partial transverse section showing a detail of construction.

In the present embodiment of the invention, a combined supporting frame for the ironing board, a clothes rack, and a clothes basket is provided, consisting of two similar folding end frames of approximately X-shape, each consisting of a long bar or leg 35 1 and a short bar or leg 2, pivoted together as indicated at 3, to fold into register with 40 each other, or to unfold into X-shape, as shown in Fig. 1.

The pivotal connection 3 is at approximately the center of the short bar 2, and the lower ends of the bars 1 and 2 at each end of the device are beveled as shown at 4, to rest smoothly upon the floor when the device is unfolded or in expanded condition.

50 The upper end of each of the short bars 2 is connected to the adjacent bar 1, by means of a link 5, each link having near one end and extending from the said end to near the other end, a longitudinally extending slot 6, and a pin 7 is passed through the slot

and through a registering opening in the upper end of the adjacent bar 2, to slidably connect the link 5 with the upper end of the bar.

The pin 7 has its opposite ends headed, as 60 shown in Figs. 1 and 2, to prevent disengagement of the pin, and the other end of each link 5 is pivotally connected to the adjacent bar 1. Each of the bars 1 is provided with a longitudinally extending slot 65 8 near its upper end, and each link 5 has an opening adapted to register with the slot of the adjacent bar 1, to receive a pin 9, which pivotally and slidably connects the link 5 with the bar 1. Each pin 9 is headed at its 70 opposite end, as shown, to prevent disengagement of the pin, and each of the said links 5 has an enlargement 10 at the end adjacent to the pin 9, which spaces the body of the bar away from the bar 1, and permits 75 the upper end of the bar 2 to slip in between the bar 1 and the link 5 when the parts are folded as shown in Fig. 5.

Referring to Fig. 2, it will be noticed that the head of the pin 7 on the inner side of 80 the bar 2 is countersunk, to be flush with the inner face of the bar to permit the bar to fold into register with the bar 1. The upper ends of the bar 1 are connected by a rounded bar or rod 11, and this bar or rod 85 serves as a rack upon which clothing may be hung. The bars 2 are connected above the pivot pins 3 by upper and lower longitudinally extending plates 12, and by inclined cross brace plates 13, which are arranged between the plates 12, and the ends of the plates 12 are secured to the outer edges of the bars 2. The bars 1 are connected at corresponding points, by upper and lower cross plates 12^a, and by cross 90 13^a, arranged between the plates 12^a. These plates 12-12^a and 13-13^a form the sides of the clothes basket when the device is expanded.

A bottom is provided for the basket, the 100 said bottom being of rectangular outline, and consisting of outer longitudinally extending plates 14, and inner plates 15, the said plates 14 and 15 being parallel, and being connected at the ends of the bottom and intermediate the ends by cross plates 16. The bottom as a whole is hinged to the lowermost longitudinal plate 12^a, by means of hinges 17, in such manner that the bottom may be folded up onto the side of the 110

basket constituted by the plates 12^a—13^a, or down into the position shown in Figs. 1 and 3 between the lowermost plates 12 and 12^a to form the bottom for the basket.

5 It will be noticed that the bars 14 of the bottom are diamond-shaped in cross section, and when the device is expanded, the outermost faces of the bars 14 fit against the inner faces of the lowermost plates 12 and 12^a.

10 The ironing board 18 is of the usual shape and the said board is provided at its large end with a transverse spacing block 19 secured to the board in any suitable or desirable manner. Near the small end, the 15 board is provided with a second spacing block 20 and these blocks are so arranged that they will rest upon the upper side edges of the links 5.

The block 19 at the large end of the board 20 is hinged to the adjacent link 5 by means of hinges 21 in such manner that the board may fold down to rest upon the link 5 above the bottom of the basket, or the board may be swung upwardly on the hinge connection 25 into the position shown in Figs. 1 and 2, where it will not interfere with access to the interior of the basket.

Carried by the link 5 at the small end of the board are two members 22 which are 30 spaced apart just far enough to permit the entrance of the spacing block 20 between them, each of these locking members or keepers 22 being provided with a socket, such as that shown at 22^a in Fig. 6. The 35 adjacent portion of the spacing block 20 is provided with a spring locking device. In the present form of the invention this locking device is shown as consisting of a cylindrical casing 23, see Fig. 6, in which a locking bolt 24 is slidably disposed, the bolt having a tapered end arranged to enter the socket 22^a. This bolt has a slidable stem 24^x which extends rearwardly through the end of the cylinder 23 and is provided with 40 a head 24^z to limit its outer movement. A spring 25 bears at one end against the cylinder and at the other end against the bolt, thus tending to force the latter outwardly. Each of the members 22 is provided with 45 beveled upper surfaces, so that all that is necessary is to bring the board into the position shown in Fig. 3, whereupon the spring locking members will enter the socket 22^a, thus retaining the board in position. A 50 slight upward pull will free the board by forcing back the spring pressed bolt 24. The keepers 22 may be of any suitable shape, but are preferably provided with flanges which extend over the sides of the member 55 5 and which are secured to the latter by means of screws 22^b, or in any other suitable manner.

The spacing block 19 is spaced far enough from the large end of the board to permit 60 the said end of the board to engage as shown

in Figs. 1 and 2, against the lower outer corner of the link 5, to support the board in the inclined position shown in these figures.

A hook 26 is pivoted to each bar 1 on the outer edge thereof between the plates 12^a, 70 and each hook is adapted to engage a headed pin 27 on the adjacent link 5 when the device is in collapsed or folded position.

The board should be brought into the position indicated in dotted lines in Fig. 1, 75 or as shown in full lines in Fig. 3, in which position the board is held securely by the keepers 22. Now, by simply taking hold of the plates or rails 12 and 12^a and drawing them together, the device will fold up into 80 the position shown in Fig. 4, for it will be observed that the sides of the members 14 which form the bottom being beveled, the bottom will automatically raise. If the edge of the bottom opposite that of the hinges 85 should slightly stick, slight upward pressure will free it, when further drawing together of the rails 12 and 12^a will result in the folding of the device. Furthermore, this folding operation will, of course, move 90 the pin 7 in the slot 6, from the outer end of the slot toward the inner end, and after the pin has passed the center of the slot, then the weight of the board will practically 95 complete the folding operation. In other words, the board will continue to move so as to bring the legs 1 and 2 into registration and also to fold up the bottom, so that the parts are all brought into the position shown in Fig. 4. The upper end of the bar 2 slips 100 in between the link 5 and the bar 1, as shown in Fig. 5, and when the bars 1 and 2 and the links 5 at each end are in registration, the bottom will be between the sides 12—13 and 12^a—13^a, as shown in Fig. 4. Now the ironing board 18 may be folded down upon the side 12—13, and the hooks 26 are engaged with the pins 27 to hold the parts in collapsed or folded condition.

When it is desired to use the device as a 110 basket or rack, the ironing board occupies the position of Figs. 1 and 2, and access to the basket is permitted. When the ironing board is to be used, it is folded down into the position of Figs. 3, 4, and 6, and the spring latch bolts 24 hold the board in 115 such position.

I claim:

1. A device of the character specified comprising a supporting frame, consisting of a plurality of pairs of crossed pivotally connected legs, a link slidably connected with the upper ends of each pair of legs to hold them in extended position when the link is horizontal and to permit the legs to fold into 120 register with each other and the link when the link is moved out of horizontal position, a rigid connection between the corresponding legs above the pivotal connection, and an ironing board having at each end a 125 130

transverse spacing block, one of the said blocks being hinged to one link to permit the board to rest upon the links or to be swung upwardly away from the links, the other block being spaced to engage the other link and said block having releasable resilient latching mechanism for holding the block to the link.

2. A device of the character specified, comprising a supporting frame consisting of a plurality of pairs of crossed pivotally connected legs, a link slidably connected with the upper ends of each pair of legs to hold them in extended position when the link is moved out of horizontal position, a

rigid connection between the corresponding legs above the pivotal connection, and an ironing board hinged to one of the links and adapted to rest upon the other when in operative position.

20

3. An ironing board comprising a supporting frame having at one end a pair of laterally spaced lugs, an ironing board hinged to the other end and adapted to swing into and out of position between the lugs, said board having a spring pressed pin adjacent to one lug and the lug having a recess for receiving the pin to hold the board in operative position.

25

CARL WILLIAM KETTLER.
